A similar pharmacological activity can be shown in a test described by Theobald et al. in Arch. int. Pharmacodyn. 148, 563 and 564 (1964) in which the dose is determined which depresses the fighting reaction of mice in 50% of the test animals (ED₅₀). Illustrative results are shown in Table II.

TABLE II

Compound tested:	ED ₅₀ mg./kg. s.c.
4 - (7,12 - dioxa-3-azaspiro[5.6]dodec-3-yl)-4'-fluorobutyrophenone hydrochloride	1.5
4 - (2 - methyl-1,5-dioxa-9-azaspiro-[5.5]undec-9-yl)-4'-fluorobutyrophenone hydrochloride	1.1
4 - (3 - phenyl-1,5-dioxa-9-azaspiro[5.5]undec-9-yl)-4'-fluorobutyrophenone hydrochloride	1.3

Another test for the depressive activity on the central nervous system is described by Theobald et al. in Arch. int. Pharmacodyn. 148, 572 (1964). According to this method, the dosage is determined at which the frequency of vomiting (induced by 0.1 mg./kg. of apomorphine hydrochloride administered subcutaneously) is reduced to 50% of its original value. Results are provided in Table III.

TABLE III

Compound tested:	ED ₅₀ mg./kg. s.c.
4 - (7,12 - dioxa-3-azaspiro[5.6]dodec-3-yl)-4'-fluorobutyrophenone hydrochloride	0.2
4 - (2 - methyl-1,5-dioxa-9-azaspiro[5.5]undec-9-yl)-fluorobutyrophenone hydrochloride	0.1
4 - (3 - phenyl-1,5-dioxa-9-azaspiro[5.5]undec-9-yl)-4'-fluorobutyrophenone hydrochloride	0.07

The sedative activity can be determined according to the method described by W. Theobald et al. in Arzneimittelforschung 9, 285-6 (1959). In this test there is measured the potentiation of anesthesia induced by a standard amount of the anesthetic 2-methoxy-4-allyl-phenoxyacetic acid diethylamide. The test animals are mice weighing between 17 and 25 g. The standard amount of anesthetic, 40 mg./kg. is administered subcutaneously. In normal animals, this dose induces shortlasting anesthesia in about half of the animals treated. An esthetized mice remain in side position which is the criterion for anesthesia. The time during which the mice remain in this side position is recorded for each animal. Thirty minutes prior to injection of the standard amount of anesthetic, the animals received the test compound in aqueous solution by subcutaneous injection. The change in duration of the anesthetic effect is calculated in percent of the effect observed with a control group. The change is expressed in percent. Representative results are shown in Table IV.

TABLE IV

Compound tested	Anesthesia potentiation	
	Dosage, mg./kg. s.c.	Change, percent
4-(1-oxa-4-thia-8-azaspiro[4,5]dec-8-yl)-4'-chlorobutyrophenone hydrochloride	20	+125
4-(1,4-dioxa-8-azaspiro[4,5]-dec-8-yl)-butyrophenone hydrochloride	20	+100
4-(3-phenyl-1,5-dioxa-9-azaspiro[5.5]undec-9-yl)-butyrophenone hydrochloride	20	+257

The toxicity of the compounds of the instant invention is low. For instances, the LD₅₀ of 4-(7,12-dioxa-3-azaspiro[5.6]dodec-3-yl)-4'-fluorobutyrophenone hydrochloride administered intravenously to mice is 51 mg./kg., the LD₅₀ of 4-(2-methyl-1,5-dioxa-9-azaspiro[5.5]undec-3-yl)-4'-fluorobutyrophenone hydrochloride in mice is 25 mg./kg. i.v. and the LD₅₀ of 4-(3-phenyl-1,5-dioxa-9-yl)-4'-fluorobutyrophenone hydrochloride is 39 mg./kg. on intravenous administration to mice.

For their intended uses the compounds of the instant invention may be administered orally in the form of aqueous solutions, including appropriate pharmaceutically acceptable acid addition salts, parenterally or rectally, preferably orally. The dosage used naturally depends on the

species, age and weight of the subject under treatment, as well as on the particular condition being treated and, of course, the mode of administration. In general, the daily dosages of the compounds used in the present invention, or their pharmaceutically acceptable acid addition salts, vary between about 0.1 and about 15 mg. per kg. of bodyweight of the mammal, preferably 0.2 mg. to 4 mg. per kg.

Therapeutic compositions consist essentially of a piperidine derivative according to the invention, or a pharmaceutically acceptable acid addition salt thereof in combination with a pharmaceutical carrier and, if desired, further additives. These compositions are presented for oral or parenteral administration in solid and liquid dosage units, respectively, such as tablets, dragees, capsules, ampoules, and the like. For rectal administration, they are presented in form of suppositories, rectal capsules, etc. Each dosage unit preferably contains between about 5 mg. to about 200 mg. of an inventive piperidine derivative or a pharmaceutically acceptable acid addition salt thereof, as active ingredient.

Suitable dosage units for oral administration such as dragees, tablets or capsules generally contain 1% to 90% of active ingredients.

Tablets and dragee cores are formed from mixtures containing the active substance in combination with solid pulverulent carriers such as lactose, saccharose, sorbitol or mannitol; starches such as potato starch, maize starch or amylopectin, laminaria powder or citrus pulp powder; cellulose derivatives or gelatin; optionally with the addition of a lubricant such as magnesium or calcium stearate or polyethylene glycols of suitable molecular weights. The dragee cores are coated, for example, with concentrated sugar solutions which can also contain, e.g. gum arabic, talcum and/or titanium dioxide, or with a lacquer dissolved in easily volatile organic solvents or mixtures of solvents. Dyestuffs can be added to these coatings to distinguish between different dosages of active substance. Other suitable oral dosage units such as hard gelatin capsules contain the active substance and the carrier, preferably as a granulate, in admixture with lubricants such as talcum or magnesium stearate and, optionally, appropriate stabilizers. In soft capsules, the active substance is preferably dissolved or suspended in suitable liquid carriers such as liquid polyethylene glycols; stabilizers can also be added.

Dosage units for rectal administration include suppositories which consist of a combination of a compound of Formula I, or a suitable salt thereof and a neutral fatty foundation as a carrier and gelatine rectal capsules which contain a combination of the active substance or a suitable salt thereof with polyethylene glycols (Carbowaxes) of suitable molecular weight as carriers.

Ampoules for parenteral, particularly intramuscular, administration preferably contain as active ingredient a water soluble pharmaceutically acceptable acid addition salt of an inventive compound, the carrier being water. The concentration of the active ingredient is preferably between 0.5% and 10.0%. If necessary, suitable stabilizing agents and/or buffer substances are added to the ampoule solutions.

The following examples will serve to further typify the nature of the present invention but should not be construed as a limitation on the scope thereof.

EXAMPLE 1

(a) A mixture of 3 g. of 1,4-dioxa-8-azaspiro[4.5]decane and 6 g. of 4'-fluoro-4-chlorobutyrophenone is refluxed for 20 hours with 5.5 g. of anhydrous potassium carbonate and 100 mg. of potassium iodide in 50 ml. of anhydrous acetone. The mixture is filtered and washed with acetone. The solvent is evaporated, the residue taken up in ether and extracted three times with 10% acetic acid. The combined acetic acid extracts are made alkaline with sodium carbonate solution and extracted with ether. The ethereal solution is dried with anhydrous sodium sul-

fate and concentrated. The 4-(1,4-dioxa-8-azaspiro[4.5]dec-8-yl)-4'-fluorobutyrophenone remains as an oil and is converted into the hydrochloride with the equimolar amount of ethereal hydrochloric acid. The hydrochloride is recrystallised from acetone, M.P. 167-170°.

The following compounds are produced in an analogous manner via the corresponding free bases:

(b) 4-(7,12-dioxa-3-azaspiro[5.6]dodec-3-yl)-4'-fluorobutyrophenone hydrochloride, M.P. 207-208°;

(c) 4-(2-methyl-1,5-dioxa-9-azaspiro[5.5]undec-9-yl)-4'-fluorobutyrophenone hydrochloride, M.P. 201-203°.

(d) 4-(3-phenyl-1,5-dioxa-9-azaspiro[5.5]undec-9-yl)-4'-fluorobutyrophenone hydrochloride, M.P. 231-233°.

(e) 4-(3,3-diethyl-1,5-dioxa-9-azaspiro[5.5]undec-9-yl)-4'-fluorobutyrophenone hydrochloride, M.P. 215°.

(f) 4-(7,16-dioxa-3-azadispiro[5.2.5.2]hexadec-3-yl)-4'-fluorobutyrophenone hydrochloride, M.P. 229-236°, of the formula

(g) 4-(1,4-dithia-8-azaspiro[4.5]dec-8-yl)-4'-fluorobutyrophenone hydrochloride; M.P. 232-237°;

(h) 4-(1,5-dithia-9-azaspiro[5.5]undec-9-yl)-4'-fluorobutyrophenone;

(i) 4-(2-methyl-1,4-dioxa-8-azaspiro[4.5]dec-8-yl)-4'-fluorobutyrophenone, M.P. 174-176°.

(j) 4-(2-methyl-1,4-dithia-8-azaspiro[4.5]dec-8-yl)-4'-fluorobutyrophenone hydrochloride; M.P. 235-240°.

(k) 4-(3-methyl-3-phenyl-1,5-dioxa-9-azaspiro[5.5]undec-9-yl)-4'-fluorobutyrophenone hydrochloride, M.P. 194-195°;

(l) 4-(5,12-dioxa-9-azadispiro[2.2.5.2]tridec-9-yl)-4'-fluorobutyrophenone hydrochloride, M.P. 220-221°, which is of the formula

(m) 4-(1,5-dihydro-spiro[2,4-benzodioxepin-3,4'-piperidine]-1'-yl)-4'-fluorobutyrophenone hydrochloride, M.P. 250-251°.

(n) 4-(1,4-dioxa-8-azaspiro[4.5]dec-8-yl)-butyrophenone hydrochloride, M.P. 187-189°.

(o) 4-(1,5-dioxa-9-azaspiro[5.5]undec-9-yl)-butyrophenone hydrochloride;

(p) 4-(2-methyl-1,5-dioxa-9-azaspiro[5.5]undec-9-yl)-butyrophenone hydrochloride;

(q) 4-(3-phenyl-1,5-dioxa-9-azaspiro[5.5]undec-9-yl)-4'-chlorobutyrophenone hydrochloride;

(r) 4-(3-methyl-3-phenyl-1,5-dioxa-9-azaspiro[5.5]undec-9-yl)-butyrophenone hydrochloride;

(s) 4-(3,3-diethyl-1,5-dioxa-9-azaspiro[5.5]undec-9-yl)-butyrophenone hydrochloride;

(t) 4-(7,12-dioxa-3-azaspiro[5.6]dodec-9-en-3-yl)-butyrophenone hydrochloride;

(u) 4-(5,12-dioxa-9-azadispiro[2.2.5.2]tridec-9-yl)-butyrophenone hydrochloride;

(v) 4-(7,16-dioxa-3-azadispiro[5.2.5.2]hexadec-3-yl)-butyrophenone hydrochloride;

(w) 4-(cis-hexahydro-spiro[1,3-benzodioxole-2,4'-piperidine]-1'-yl)-butyrophenone hydrochloride;

(x) 4-(1,5-dihydro-spiro[2,4-benzodioxepin-3,4'-piperidine]-1'-yl)-butyrophenone hydrochloride;

(y) 4-(3-ethyl-3-phenyl-1,5-dioxa-9-azaspiro[5.5]undec-9-yl)-butyrophenone hydrochloride.

(z) 4-(1-oxa-4-thia-8-azaspiro[4.5]dec-8-yl)-4'-chlorobutyrophenone hydrochloride.

The azaspiro-alkanes used as starting materials are prepared according to the following procedure:

A mixture of 30 g. of 4,4-dihydroxy-piperidine hydrochloride, 17 g. of 1,2-dihydroxypropane and 1 g. of p-

toluenesulfonic acid and 500 ml. of benzene is stirred and refluxed under a water separator. When the azeotropic distillation of water is finished, the benzene is decanted and 100 ml. of 50% potassium carbonate solution and 200 ml. of chloroform is added to the stirred residue. The chloroform phase is removed and the aqueous phase is extracted several times with chloroform. The combined chloroform phases are washed with water, dried and concentrated to give 2-methyl-1,4-dioxa-9-azaspiro[4.5]decane which is distilled at 95°/12 torr. (Starting material for (i).)

The following starting materials are obtained analogously by reacting the 4,4-dihydroxy-piperidine hydrochloride with the pertinent dihydroxy, hydroxy-mercapto or dimercapto compounds:

15 1,4-dioxa-8-azaspiro[4.5]decane (starting material for (a) and (n));

7,12-dioxa-3-azaspiro[5.6]dodecane, B.P. 113-115°/11 torr (starting material for (b));

2-methyl-1,5-dioxa-9-azaspiro[5.5]undecane, B.P. 20 107°/10 torr (starting material for (c) and (p));

3-phenyl-1,5-dioxa-9-azaspiro[5.5]undecane, B.P.

137°/0.01 torr (starting material for (d) and (q));

3,3-diethyl-1,5-dioxa-9-azaspiro[5.5]undecane, B.P.

145-149°/12 torr (starting material for (e) and (s));

25 7,16-dioxa-3-azadispiro[5.2.5.2]hexadecane, B.P.

100-110°/0.001 torr (starting material for (f) and (v));

1,4-dithia-8-azaspiro[4.5]decane (starting material for (g));

30 1,5-dithia-9-azaspiro[5.5]undecane (starting material for (h));

2-methyl-1,4-dithia-8-azaspiro[4.5]decane (starting material for (j));

3-methyl-3-phenyl-1,5-dioxa-9-azaspiro[5.5]undecane, 35 B.P. 145-150°/0.001 torr (starting material for (k) and (r));

5,12-dioxa-9-azadispiro[2.2.5.2]tridecane, B.P. 131-144°/11 torr (starting material for (l) and (u));

1,5-dihydro-spiro[2,4-benzodioxepin-3,4'-piperidine] (starting material for (m));

40 1,5-dioxa-9-azaspiro[5.5]undecane (starting material for (o));

7,12-dioxa-3-azaspiro[5.6]dodec-9-ene, B.P. 128°/12 torr (starting material for (t));

45 cis-hexahydro-spiro[1,3-benzodioxole-2,4'-piperidine], B.P. 128-130°/10 torr (produced using cis-1,2-cyclohexanediol, it is the starting material for (w));

1,5-dihydro-spiro[2,4-benzodioxepin-3,4'-piperidine], M.P. 120-121° (produced using o-xylene- α , α' -diol);

50 it is the starting material for (x));

3-ethyl-3-phenyl-1,5-dioxa-9-azaspiro[5.5]undecane (starting material for (y));

1-oxa-4-thia-8-azaspiro[4.5]decane (starting material for (z)).

EXAMPLE 2

250 g. of 4-(1,4-dioxa-8-azaspiro[4.5]dec-8-yl)-4'-fluorobutyrophenone hydrochloride, are mixed with 175.80 g. of lactose and 169.70 g. of potato starch, the mixture is moistened with an alcoholic solution of 10 g. of stearic acid and granulated through a sieve. After drying, 160 g. of potato starch, 200 g. of talcum, 250 g. of magnesium stearate and 32 g. of colloidal silicium dioxide are mixed in and the mixture is pressed into 10,000 tablets each weighing 100 mg. and containing 25 mg. of active substance. If desired, the tablets can be grooved to attain better adaptation of the dosage.

EXAMPLE 3

A granulate is produced from 250 g. of 4-(7,12-dioxa-3-azaspiro[5.6]dodec-3-yl)-4'-fluorobutyrophenone hydrochloride, 175.90 g. of lactose and the alcoholic solution of 10 g. of stearic acid. After drying, 56.60 g. of colloidal silicium dioxide, 165 g. of talcum, 20 g. of potato starch and 2.50 g. of magnesium stearate are mixed in

and the whole is pressed into 10,000 dragee cores. These are then coated with a concentrated syrup made from 502.28 g. of crystallized saccharose, 6 g. of shellac, 10 g. of gum arabic, 0.22 g. of dyestuff and 1.5 g. of titanium dioxide and dried. Each of the dragees obtained weighs 120 mg. and contains 25 mg. of active substance.

EXAMPLE 4

250 g. of 4-(1,5-dioxa - 9 - azaspiro[5.5]undec-9-yl)-4'-fluorobutyrophenone hydrochloride are well mixed with 442.8 g. of potato starch and 295.2 g. of lactose, the mixture is moistened with an alcoholic solution of 30.0 g. of stearic acid and granulated through a sieve. After drying, this granulate is mixed with 96.0 g. of talcum, 80.0 g. of potato starch and 6.0 g. of magnesium stearate and the mixture obtained is again granulated through a sieve. This granulate serves as filling for 10,000 hard gelatine capsules each weighing 120 mg., and each of the capsules so obtained contains 25 mg. of active substance.

EXAMPLE 5

4 - (3 - phenyl - 1,5 - dioxa - 9 - azaspiro[5.5]undec-9-yl)-4' - fluorobutyrophenone hydrochloride are introduced into a two-piece gelatine No. 1 capsule.

EXAMPLE 6

1.0 g. of 4-(2-methyl - 1,5 - dioxa - 9-azaspiro[5.5]undec - 9 - yl) - 4' - fluorobutyrophenone hydrochloride and 0.10 g. of ascorbic acid are dissolved in distilled water and the solution is diluted up to 100 ml. The solution obtained is used to fill ampoules each containing 1 ml. which corresponds to a content of 10 mg. of the active butyrophenone. The filled ampoules are then sterilized by heating in the usual way.

EXAMPLE 7

15 mg. of 4 - (1 - oxa - 4 - thia - 8 - azaspiro[4.5]dec-8-yl - 4' - chlorobutyrophenone hydrochloride are introduced into a two-piece gelatin No. 1 capsule.

EXAMPLE 8

250 g. of 4-(3-phenyl - 1,5 - dioxa - 9 - azaspiro[5.5]undec - 9 - yl) - 4' - fluorobutyrophenone hydrochloride, 175.9 g. of lactose and 169.7 g. of potato starch are mixed and the mixture is moistened with an alcoholic solution of 10 g. of stearic acid and granulated through a sieve. After drying, 160 g. of potato starch, 200 g. of talcum, 2.5 g. of magnesium stearate and 32 g. of colloidal silicon dioxide are mixed and the mixture is pressed into 10,000 tablets each weighing 100 mg. and containing 25 mg. of the active butyrophenone. If desired, the tablets can be grooved to enable better adaptation of the dosage instructions.

EXAMPLE 9

10 mg. of 4-(7,12-dioxa - 3 - azaspiro[5.6]dodec-3-yl)-4'-fluorobutyrophenone hydrochloride are introduced into a two-piece gelatine No. 1 capsule.

EXAMPLE 10

10 mg. of 4-(1,4-dioxa - 8 - azaspiro[4.5]dec-8-yl)-4'-fluorobutyrophenone hydrochloride are introduced into a two-piece gelatine No. 1 capsule.

EXAMPLE 11

10.0 g. of 4-(2-methyl - 1,5 - dioxa - 9 - azaspiro[5.5]undec - 9 - yl) - 4' - fluorobutyrophenone hydrochloride, 30.0 g. of lactose and 5.0 g. of highly dispersed silicic acid are mixed, the mixture is moistened with a solution of 5.0 g. of gelatine and 7.5 g. of glycerine

in distilled water and granulated through a sieve. The granulate is dried, sieved and carefully mixed with 3.5 g. of potato starch, 3.5 g. of talcum and 0.5 g. of magnesium stearate. The mixture is pressed into 1,000 tablets each weighing 65 mg. and containing 10 mg. of active substance.

EXAMPLE 12

10.0 g. of 4-(3-phenyl - 1,5 - dioxa - 9 - azaspiro[5.5]undec - 9 - yl)-butyrophenone hydrochloride, 15 g. of lactose and 20 g. of starch are mixed, the mixture is moistened with a solution of 5.0 g. of gelatine and 7.5 g. of glycerin in distilled water and granulated through a sieve. The granulate is dried, sieved and carefully mixed with 3.5 g. of potato starch, 3.5 g. of talcum and 0.5 g. of magnesium stearate. The mixture is pressed into 1,000 dragée cores. These are then coated with a concentrated syrup of 26.660 g. of crystallised saccharose, 17.500 g. of talcum, 1.000 g. of shellac, 3.750 g. of gum arabic, 20.000 g. of highly dispersed silicic acid and 0.090 g. of dyestuff and dried. The dragées obtained each weigh 115 mg. and contain 10 mg. of active substance.

Percentages in the preceding specification and in these examples are given by weight; the temperatures are given in degrees centigrade; torr means mm. Hg.

What is claimed is:

1. A therapeutic composition for producing a sedative and depressant effect comprising (a) an effective amount of a compound of the formula

wherein

R is a divalent hydrocarbon having 2 to 11 carbon atoms, no more than four of which separate X and Y;

each of X and Y, independent of the other, is oxygen or sulfur; and

R₁ is hydrogen, chloro or fluoro or a pharmaceutically acceptable acid addition salt thereof and (b) a pharmaceutical carrier.

2. A therapeutic composition as defined in claim 1 wherein R is a divalent hydrocarbon of from 2 to 11 carbon atoms, no more than four of which separate X and Y, X and Y are oxygen and R₁ is fluoro.

3. A therapeutic composition as defined in claim 1 wherein R is tetramethylene, X and Y are oxygen and R₁ is fluoro.

4. A therapeutic composition as defined in claim 1 wherein R is 2-phenyltrimethylene, X and Y are oxygen and R₁ is fluoro.

5. A method of producing a sedative and depressant effect in a mammal which comprises administering to said mammal an effective amount of a compound of the formula:

wherein

R is a divalent hydrocarbon having from 2 to 11 carbon atoms, no more than four of which separate X and Y;

each of X and Y, independent of the other, is oxygen or sulfur; and

R₁ is hydrogen, chloro or fluoro or a pharmaceutically acceptable acid addition salt thereof.

6. A method as defined in claim 5 wherein R is a divalent hydrocarbon of from 2 to 11 carbon atoms, no more than four of which separate X and Y, X and Y are oxygen and R₁ is fluoro.

7. A method as defined in claim 5 wherein R is tetra-methylene, X and Y are oxygen and R₁ is fluoro.

8. A method as defined in claim 5 wherein R is 2 - phenyltrimethylene, X and Y are oxygen and R₁ is fluoro.
